CLAIM

The ornamental design for linen with border, as shown and described.

DESCRIPTION

FIG. 1 is a plan view of linen with border in the form of a pillowcase showing a first embodiment of my new design with an ornamental border along one edge;

FIG. 2 is a front end view of the pillowcase of FIG. 1;

FIG. 3 is a right side view of the pillowcase of FIG. 1;

FIG. 4 is a plan view of linen with border in the form of a sheet showing a second embodiment of my new design with an ornamental border along one edge. The plan view is shown broken away both vertically and horizontally to indicate indeterminate length and width, it being understood that the border pattern is repeated uniformly throughout the length and width thereof; and,

FIG. 5 is an enlarged fragmentary plan view of a portion of the border pattern shown in FIGS. 1 and 4 in greater detail.
